(57) **CLAIM**

The ornamental design for a light therapy apparatus, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1.1 is a top perspective view of a light therapy apparatus; and

FIG. 1.2 is a bottom perspective view thereof.

The broken lines depict portions of the light therapy apparatus that form no part of the claimed design.
